UNITED STATES PATENT OFFICE.

CHARLES E. WAREAM, OF CINCINNATI, AND DANA H. BENJAMIN, OF CLEVELAND HEIGHTS, OHIO, ASSIGNEES TO THE AMERICAN LAUNDRY MACHINERY COMPANY, OF CINCINNATI, OHIO, A CORPORATION OF OHIO.

SHIRT BOARD FOR IRONING MACHINES.

Original application filed July 2, 1917, Serial No. 178,286. Divided and this application filed July 18, 1917, Serial No. 181,395. Renewed July 18, 1921. Serial No. 485,787.

To all whom it may concern:

Be it known that we, CHARLES E. WAREAM and DANA H. BENJAMIN, citizens of the United States, residing at Cincinnati and Cleveland Heights, respectively, in the counties of Hamilton and Cuyahoga and State of Ohio, have invented certain new and useful Improvements in Shirt Boards for Ironing Machines, of which the following is a specification.

This invention relates to ironing machines, and more particularly to the shirt board for holding the work while ironing the same.

The objects of the invention are to provide improved means for clamping or holding the ends of the neck-band while and after expanding the neck-band former therein; to enable said clamping or holding means to be operated conjointly with or to be coupled with the device for actuating the neck band former; to enable the neck-band clamping device to be set lightly with the fingers and subsequently more firmly by suitable mechanism for insuring correct position of the shirt neck-band; to improve the shape of the ironing board, especially at the shoulder end, to enable the shirt to be dressed thereon with the tails spread and so ironed, but nevertheless securing proper slope or inclination of the shoulder folds when the shirt is folded up and buttoned after ironing; and finally, to generally improve the construction of the board itself and its operating mechanism to secure improved quality in the ironing work performed on the machine.

Further objects of the invention are in part obvious and in part will appear more in detail hereinafter. The invention comprises the shirt ironing board hereinafter described and claimed.

In the drawings, which represent one embodiment of the invention, Fig. 1 is a central longitudinal elevation; Fig. 2 is a cross section on the line 2—2 Fig. 1; Fig. 3 is a similar section on the line 3—3 Fig. 1; Fig. 4 is a plan view on a reduced scale; Fig. 5 is a plan view on a larger scale of the neck band former, the board itself being omitted; Fig. 6 is a detail cross section on the line 6—6 Fig. 5; Fig. 7 is a central longitudinal section on the line 7—7 Fig. 5 and Fig. 8

is a detail cross section on the line 8—8 Fig. 5.

This application is a division of our pending application for ironing machines filed July 2, 1917, Serial No. 178,286, and the shirt board shown, described, and claimed herein is one of the forms of shirt boards illustrated and described in said parent application, and is adapted for use with the same or any suitable form of ironing machine. This shirt board illustrated in the drawings and hereinafter described in detail is so arranged as to enable the shirt to be dressed thereon in form to be ironed and while on the board is brought into ironing relation with a suitable ironing member for ironing the shirt. Since this organization is well known in the art no further description thereof is required.

Referring now to the drawings, 1 indicates a suitable support, which may be either stationary or movable according to the character of the particular machine with which the board is used. On the present machine this support is in the form of a hollow sleeve to receive a post 2 depending from the base 3 of the frame carrying the shirt board. The sleeve 1 may also be provided with a laterally extending arm 4, having an opening to receive a rod or bar 5 depending from the base 3. This arrangement enables the frame and attached shirt board to be raised and lowered in the sleeve, but prevents rotation of the frame 3 therein. The frame 3 is provided with upwardly extending webs 6 which support the block 7 attached to the under side of a longitudinal bar 8 lying in a recess of the board 9 beneath the padding 10 thereon. This bar extends from the tail end of the board to a point near the neck band end thereof where it is provided with a recess to receive vertical pins 11 on which are located sleeves 12 mounted in recesses in the stationary forward portion 13 of the neck-band former. The sleeves 12 can rise and fall on the pins with the ironing motion, so as to allow the neck band former to sink with the padding when ironing pressure is applied to the shirt, but prevents any horizontal motion of the stationary member 13 of the neck-band former relative to the supporting frame 3. Consequently if the co-operating

ironing member is in fixed relation with the frame 3, the curve of the recess in said ironing member will always lie in proper registering relation with the stationary portion 13 of the neck-band former.

Suitable means is provided for enabling the size of the neck-band former to be varied to accommodate shirts of various sizes and to also enable the neck-band former 10 to be expanded in the neck-band of the shirt and to produce the proper form thereof. The expanding movement is secured by moving back the back portions of the neck-band former, but as the curve of the neck-band former always bears a definite relation to the folding line at the yoke end of the shirt board, the board is moved back with the back portions of the neck-band former. This arrangement maintains the folding line 15 at the neck-band end of the shirt substantially tangent to the curve at the back of the neck-band in all sizes to which the neck-band former is adjusted.

The shirt board 9 is attached to and is 25 carried by a hollow frame 14 having a base 15 sliding on V ways of the base 3 (see Fig. 3). At one end the board 9 carries the back yoke receiving frame 16 from which rises a plate 17 having a head 18 provided with a 30 recess to receive a transversely extending rod 19 whose ends enter openings in the adjustable back portions 20 of the neck band former. Said back portions are attached to pins or rods 20^a which enter horizontal openings 35 in the stationary forward portion 13 of the neck band former, said openings diverging from the tail toward the neck-band end of the shirt board, as shown in Fig. 5. When the frame 14 with the attached shirt board 40 9 is moved rearwardly rod 19 is carried back and moves with it the adjustable rear portions 20 of the neck-band former, said portions also moving outwardly from the full line to the dotted line position Fig. 5 45 thereby expanding the neck-band former but substantially maintaining its neck-band shape or form.

The back yoke receiving member may be 50 heated in any suitable manner, such as by electric current supplied to an electric heating unit therein, as in the parent application before referred to, but is here shown as heated by steam or other heating medium introduced to the hollow heating chamber 55 21 thereof through the pipe 22.

In this machine the shirt is dressed upon the board with its tails diverging and with the button and button-hole strips extending in diverging lines parallel with the edges 23 60 of the board, the shirt board being of what is known as the keystone type its side edges diverging from the neck-band end toward the tail end, as shown in Fig. 4. The end edges 24 of the board, whose lines are maintained substantially tangent to the back of

the neck-band former, as before described, also diverge and extend backwardly and outwardly away from the neck-band former. They may diverge on straight diagonal lines but are shown as diverging in a gradual 70 curve. These edges of the board co-operate with the back yoke ironer when the latter is brought into ironing engagement with the back yoke receiving portion 16 of the board to produce the folding lines in the 75 yoke. When the shirt is set up on this board with said folding lines inclined backwardly and outwardly, as shown, and with the tails spread, the shirt will take the proper desired form when buttoned up after its removal from the board. In other words, by curving or inclining the end edges of the board and the cooperating back yoke ironer compensation is made for abnormal divergence of the tails, so that when the shirt is 80 85 closed up in final form its shoulders have the proper desirable slope.

The neck-band of the shirt is applied to the neck-band former unbuttoned, its edges merely meeting or abutting, although they 90 may lap slightly if desired. The absence of buttons requires the meeting ends of the shirt neck-band to be clamped or held against the stationary front portion of the neck-band former before expanding the 95 former in the neck-band to avoid separating the meeting ends of the neck-band. For this purpose we provide the neck-band clamping member 25 shown in Figs. 5 and 7, and comprising the body portion 26 sliding in a 100 recess in the top of the stationary portion 13 of the neck-band former and having a depending flange 27 lying in front of said former and whose inner surface next to the neck band may be padded or otherwise provided with a suitable yielding clamping surface 28. This clamping device is either rigidly or pivotedly attached to a rod 29 around which is a spiral compression spring 30 tending to move said clamping member away 105 from the neck-band former or to the release position. Rod 29 extends rearwardly 110 through an opening in an L shaped locking member 31 and then through an opening in the upwardly extending portion 32 of a slide 33 movable longitudinally in the body 13 of the neck-band former and provided with a recess 34 to receive the lower edge of the locking member 31. A light compression spring 35 is located between 115 members 31 and 32 and tends to move member 31 forwardly or to the right in Fig. 7. The opening in said member is slightly larger than the rod 29, so that when the vertical portion of member 31 assumes a 120 position askew to the axis of rod 29 under the influence of spring 35 it grips the rod and prevents it from moving forwardly. Pressure applied by the fingers to the clamping member 27 to push the same backwardly 125 130

- will swing member 31 backwardly about its lower edge, release the rod and allow it to move rearwardly. This arrangement enables the shirt to be pressed upon the board 5 with the neck-band surrounding the neck-band former and the clamping member to be pushed backwardly by the fingers or thumb into light temporary clamping engagement with the neck-band former.
- 10 Slide 33 is also provided with a depending notched portion 36 to receive an upwardly extending toe 37 on the bar 38 which slides in a recess or channel of the bar 8, and whose forward end (see Fig. 1) is suitably connected to operating mechanism, as shown said bar is pivotally connected to one arm of a lever 39 whose other arm is pivotally connected to a rod 40. By pulling on said rod the slide 38 is moved rearwardly carrying 15 with it member 31 and moving the clamping member 27 into more firm clamping engagement with the neck-band.
- The mechanism for actuating the rod 40 to secure powerful clamping pressure is 20 preferably associated with the mechanism for expanding the neck-band former, so that both the clamping pressure and the expansion of the neck-band former may be secured by a single operation.
- 25 In the form shown in the drawings the webs 6 of the base 3 serve to support a cross shaft 41 carrying a gear segment 42 and a cam 43. Segment 42 co-operates with the gear segment 44 rotating on a shaft 45 also 30 supported by the webs 6 and having a depending arm 46 provided with a roller 47 which is movable between an abutment 48 on the board carrying frame 14 and a cross bar 49 also attached to and forming a part of 35 the frame 14 and which extends across between the side walls thereof. Arm 46 is also provided with a laterally extending pin 50 which engages the depending arm 51 of a lever pivoted on a shaft 52 extending across 40 between the walls of the movable frame 14 and whose other arm 53 carries a roller 54 lying beneath a horizontal arm 55 of a latch lever pivoted on shaft 56 carried by the webs 6 and having a depending arm 57 provided 45 with a toe 58 lying at one side of a rod 59 attached to the cross member 49 and extending through guiding openings in portions of the frame 3. Said toe lies in front of a locking member 60 having a base 61 seated 50 in the frame and which locking member surrounds the shaft 59 and has an opening slightly larger than said shaft. This locking member is similar in construction and operation to the member 31 before described, 55 when it assumes a position askew relative to the axis of the rod 59 it grips the same and prevents it from moving to the right. Said locking member is moved to the right or to locking position by the compression 60 spring 62 acting on a collar 63 sliding on

said rod and abutting small projections on the member 60.

Cam 43 lies opposite and cooperates with a roller 64 on the lower arm 65 of a lever whose upper arm is pivotally connected to a sleeve 66 having a sliding movement on the rod 40 and lying adjacent a light compression spring 67 between said sleeve 66 and adjustable nuts 68 on the end of said rod. Rod 40 is also provided with a collar 69 75 serving as a seat for one end of the compression spring 70 whose opposite end abuts a seat on the frame 14. Shaft 41 extends out through one of the webs 6 and its outer end is provided with an operating handle or lever 71 for manipulation by the operator.

In preparing the shirt for ironing it is dressed upon the board with the ends of the neck-band meeting or overlapping beneath the clamping member 27 which is pushed up into light clamping engagement with the neck-band. The body 13 of the neck-band former is usually provided with an undercut groove or channel 72 Fig. 6, to receive the neck-band, and the clamping pressure of the neck-band clamping member forces the neck-band into its seat in said channel. Lever 71 is then turned in a counter clock-wise direction Fig. 1. The first motion of said lever

causes cam 43 to move the roller 64 to the left and apply a yielding pull through the spring 67 to the rod 40, thereby oscillating lever 39 in a counter clock-wise direction and through the mechanism described applying powerful clamping pressure to the member 27 of the neck-band. Lever 71 is moved until the roller 64 rides up upon the outer circumference of cam 43, springs 67 and 70 allowing additional motion of lever 71 after full clamping action has been secured. Further motion of lever 71 has no effect upon the clamping action.

The first motion of lever 71 also oscillates gear segment 42 and turns arm 46 in a clock-wise direction Fig. 1. Roller 47 moves to the left and releases the lever 51, 53 which has been held in the position shown in Fig. 1 by the pin 50. The arm 53 of said lever therefore allows arm 55 to drop moving the toe 58 away from the latch 60. By the time roller 64 reaches the top of cam 43, roller 47 has reached the abutment 48 and further motion of lever 71 causes the frame 14 of the shirt board 9 with the padding thereon to move to the left in Fig. 1, carrying back the rod 19 and expanding the neck band former in the neck-band of the shirt. As the frame 14 moves backwardly rod 59 slides loosely through the latch 60, but said latch prevents return movement of the said slide. Lever 71 is lifted until the neck-band is fully clamped and the neck-band former is fully expanded in the neck-band. The shirt is then ready to be ironed either by a hand iron or by bringing the board with the shirt

thereon into co-operation with a suitable ironing member. When the shirt has been ironed it is released from the board by moving lever 71 in a clock-wise direction. The first downward movement of said lever moves the roller 47 away from the abutment 48 and brings pin 50 into engagement with the lever arm 51, causing arm 53 to rise. Roller 54 on said arm engages arm 55 and turns the lever 55, 57 in a clockwise direction Fig. 1 advancing the toe 58 into engagement with the latch, thereby turning said latch and releasing the rod 59 therefrom. Further downward movement of lever 71 causes the roller 47 to engage the cross bar 49 and moves the frame 14 to the right in Fig. 1, collapsing the neck-band former. This movement continues until the roller 64 leaves the circumference of cam 43, whereupon the lever 55 is turned in a counter clock-wise direction Fig. 1 by the spring 67, which permits motion of rod 40 to release lock 31 and allows the neck-band clamping member 27 to move to release position, permitting the ironed shirt to be removed from the board.

The shirt is ironed with the folding line diverging at the yoke but the tails are spread. Consequently when the shirt is finally buttoned up the folding line is straightened out at the shoulders and the proper desired slope of the shoulders is secured.

The construction described enables the shirts to be ironed more rapidly and with better results than prior constructions for the purpose.

What we claim is:

1. A shirt ironing board having its end edges at the neck-band receiving end diverging outwardly and backwardly, and a neck-band former on said board, said end edges being substantially tangent to the curve of the neck-band former.
2. A shirt-ironing board having its side edges diverging from the neck-band end toward the tail end and its end edges at the neck-band end diverging outwardly and backwardly, and a neck-band former on said board, said end edges being substantially tangent to the curve of the neck-band former.
3. A shirt ironing board having its side edges diverging from the neck-band end toward the tail end and its end edges at the neck-band end diverging outwardly and backwardly, a neck-band former on said board, said end edges being substantially tangent to the curve of the neck-band former, and means for adjusting the size of said neck-band former without disturbing the tangent relation of the end edges of the board thereto.
4. In combination, an ironing board for supporting a shirt to be ironed, an adjustable neck-band former thereon, means car-

ried by said former for clamping the neck-band to said former, and common operating means for said clamping means and adjustable former.

5. In combination, an ironing board for supporting a shirt to be ironed, an adjustable neck-band former thereon, a neckband clamp, and common means adapted when operated to adjust said former and also operate said clamp.

6. In combination, an ironing board for supporting a shirt to be ironed, an adjustable neck-band former thereon, means for clamping the shirt neck-band to said former, and common means operable from the tail end of said board for both adjusting said former and also operating said clamping means.

7. In combination, an ironing board for supporting a shirt to be ironed, an adjustable neck-band former thereon, an operating member, actuating connections between said member and adjustable former, a neckband clamp, and means whereby said neck-band clamp is also operated by said member.

8. In combination, an ironing board for supporting a shirt to be ironed, an adjustable neck-band former thereon, a neck-band clamp, an operating member, operating connections between said member and adjustable former, and between said member and clamp, and a lost motion connection in said mechanism.

9. In combination, an ironing board for supporting a shirt to be ironed, an adjustable neck-band former thereon, a neck-band clamp, an operating member, operating connections between said member and adjustable former and between said member and clamp, the connection between said operating member and clamp being yielding.

10. In combination, an ironing board for supporting a shirt to be ironed, an adjustable neck-band former thereon, a neck-band clamp, an operating member, operating mechanism between said member and adjustable former and between said member and clamp, and a lost motion connection between said operating member and adjustable former.

11. In combination, an ironing board for supporting a shirt to be ironed, an adjustable neck-band former thereon, a neck-band clamp, an operating member, operating mechanism between said member and adjustable former and between said member and clamp, a yielding connection between said operating member and clamp, and a lost motion connection between said operating member and adjustable former.

12. In combination, an ironing board for supporting a shirt to be ironed, an adjustable neck-band former thereon comprising a plurality of portions the relation of the front one of which to said board may be ad-

justed, and a neck-band clamp carried by said front neckband former portion.

13. In combination, a support, an ironing board thereon, a neck-band former carried by said ironing board and comprising several portions, one of which is stationary relative to said support, said stationary portion carrying a neck-band clamp, and means for adjusting said former and actuating said clamp.

14. In combination, a support, an ironing board adjustable thereon, a neck-band former carried by said ironing board and comprising several portions, one of which is stationary relative to said support, said stationary portion carrying a neck-band clamp, and means carried by said support and adapted when operated to actuate said clamp and adjust said former.

20 15. In combination, a support, an ironing board adjustable thereon, spaced abutments movable with said board, an adjustable neckband former including a member carried by said support and members adjustable with said board, and an operating member movably mounted on said support and having a portion movable between said spaced abutments for operative engagement therewith.

30 16. In combination, a support, an ironing board adjustable thereon, spaced abutments movable with said board, an adjustable neckband former including a front member carried by said support and rear members adjustable with said board, a neckband clamp on said front member, a rod for operating the same, a movable member on said support having a portion movable between said spaced abutments for operative engagement therewith, and means on said support for actuating said rod and movable member.

40 17. In combination, a support, an ironing board adjustable thereon, spaced abutments movable with said board, an adjustable neckband former including a front member carried by said support and rear members adjustable with said board, a neckband clamp on said front member, a rod for operating the same, and two swinging levers on said support, one for actuating said rod and the other having a portion movable between said abutments for operative engagement therewith.

55 18. In combination, a support, an ironing board adjustable thereon, spaced abutments movable with said board, an adjustable neckband former including a front member carried by said support and rear members adjustable with said board, a neckband clamp on said front member, a rod for operating the same, two swinging levers on said support, one for actuating said rod and the other having a portion movable between said abutments for operative engagement there-

with, and means co-operating with said last named lever for locking the neckband former in any position to which it may be adjusted.

19. In combination, a support, an ironing board adjustable thereon, spaced abutments movable with said board, an adjustable neckband former including a front member carried by said support and rear members adjustable with said board, a neckband clamp on said front member, a rod for operating the same, two swinging levers on said support, one for actuating said rod and the other having a portion movable between said abutments for operative engagement therewith, means co-operating with said last named lever for locking the neckband former in any position to which it may be adjusted, and means actuated by said last named lever for releasing said lock.

20. In combination, a support, an ironing board adjustable thereon, spaced abutments movable with said board, an adjustable neckband former including a front member carried by said support and rear members adjustable with said board, a neckband clamp on said front member, a rod for operating the same, two swinging levers on said support, one for actuating said rod and the other having a portion movable between said abutments for operative engagement therewith, an operating lever, a cam actuated thereby for operating the first named of said two levers, and gear segments actuated by said operating lever for actuating the second of said two levers.

21. An ironing board, comprising a support, a padded work receiving board on said support, a neckband former and clamp structure resting on the padding of said board, said structure and board being freely and relatively movable normally to the plane of the board so that the structure rests at all times on the padding regardless of the thickness of the padding.

22. An ironing board, comprising a support, a padded work receiving board on said support, a neckband former and clamp structure resting on the padding of said board, said structure and board being freely and relatively movable normally to the plane of the board so that the structure rests at all times on the padding regardless of the thickness of the padding, said neckband former and structure including an expandible former and a clamp for the neckband thereon, and common operating means for expanding said former and operating said clamp.

23. An ironing board, comprising a support, a padded work receiving board thereon, a neckband former resting on the padding of said board and freely movable normally to the plane of the board to rest on said padding regardless of the thickness

thereof, and a neckband clamp carried by said neckband former.

24. An ironing board, comprising a support, a padded work receiving board thereon, a neckband former resting on the padding of said board and freely movable normally to the plane of the board to rest on said padding regardless of the thickness thereof, a neckband clamp carried by said

neckband former, said neckband former being adjustable to various sizes, and common operating means for adjusting said former and operating said clamp.

In testimony whereof we affix our signatures.

CHARLES E. WAREAM.
DANA H. BENJAMIN.
